[57] CLAIM

The ornamental design for a copy machine book support, as shown.

DESCRIPTION

FIG. 1 is a perspective view of a copy machine book support showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left-side elevational view thereof;

FIG. 7 is a right-side elevational view thereof;

FIG. 8 is a perspective view of a second embodiment of my new design of FIGS. 1-7;

FIG. 9 is a top plan view thereof;

FIG. 10 is a front elevational view thereof;

FIG. 11 is a bottom plan view thereof;

FIG. 12 is a rear elevational view thereof;

FIG. 13 is a left-side elevational view thereof; and,

FIG. 14 is a right-side elevational view thereof.

FIG. 4

FIG. 5

FIG. 6

FIG. 7

FIG. 8

FIG. 9
